(74) *Attorney, Agent, or Firm* — Ward and Smith, P.A.;
Ryan K. Simmons

(57) **CLAIM**

The ornamental design for a food carton, as shown and described.

DESCRIPTION

FIG. 1 is a perspective view of a first embodiment of a food carton showing a new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a perspective view of the food carton of FIG. 1 showing it in an open configuration;

FIG. 9 is a top plan view thereof;

FIG. 10 is a bottom plan view thereof;

FIG. 11 is a perspective view of the food carton of FIG. 1 showing a flap being removed therefrom;

FIG. 12 is a perspective view of a second embodiment of a food carton showing a new design;

FIG. 13 is a left side elevation view thereof;

FIG. 14 is a right side elevation view thereof;

FIG. 15 is a front elevation view thereof;

FIG. 16 is a rear elevation view thereof;

FIG. 17 is a top plan view thereof;

FIG. 18 is a bottom plan view thereof;

FIG. 19 is a perspective view thereof, showing it in an open configuration;

FIG. 20 is a top plan view thereof;

FIG. 21 is a bottom plan view thereof; and,

FIG. 22 is a perspective view of FIG. 19 showing a flap being removed therefrom.

In the drawings the dotted lines are for the purpose of illustrating perforations and form part of the claimed design; and the dash-dash broken lines are for the purpose of illustrating environment only and form no part of the claimed design.

1 Claim, 18 Drawing Sheets
